HOBBLE

Warren J. Heimer, Denver, Colo.

Application August 16, 1937, Serial No. 159,284

4 Claims. (Cl. 119—128)

This invention relates to improvements in hobbles and relates more particularly to that type of hobble employed with milk cows to prevent kicking while being milked.

5 It is frequently necessary to hobble young cows, and sometimes old ones, to keep them from kicking. This is especially true when the cows are being trained to be milked by machines.

It has long been customary to apply to cows 10 anti-kicking hobbles comprising two open hooks attached to each other by a rope, chain or strap, which are also frequently provided with means for adjusting the distance between the hooks.

15 It frequently happens that when the hobbles are first applied to cows, they become frantic when they discover that they are hobbled, and in their efforts to dislodge the hobbles, they often tear the skin or make themselves sore by the rubbing and chafing action of the chains, ropes 20 or straps.

Even after the cow has been trained so that she will no longer fight the hobble, her legs are frequently irritated due to the chafing action of the chains, ropes or straps, as they are moved 25 over the skin due to the frequent but slight movement of the legs that almost invariably takes place when the cow is being milked.

It is the principal object of this invention to produce a hobble of such construction and design 30 that it will afford protection against irritation or chafing or other injury due to the action of the strap which connects the two hooks.

This invention, briefly described, comprises two metal hooks, of such shape and design that they 35 will fit over the tendon above the hock, each having attached to it a piece of leather, or other similar material, of such length that when the hooks are in position the leather flaps will extend to the front of the legs and preferably extend a short distance across the same. Each leather 40 flap is provided on the outside with an elongated loop extending entirely across the wide free end. A leather strap is secured to each flap and passes through the loop in such a way that it can slide 45 along the outer surfaces of the flaps to the extent permitted by the loops, the function of the flaps being primarily to protect the cow's legs from the rubbing action of the straps.

Having thus briefly described the invention, it 50 will now be described in detail and for this purpose reference will be had to the accompanying drawing in which the invention has been illustrated in its preferred form and in which:

Figure 1 is a view showing the position occupied 55 by the hobble when in place on a cow's legs;

Figure 2 is a view showing the hobbles as they would appear if viewed through plane 2—2 Fig. 1;

Figure 3 is a plan view of the hobble showing the same extended and as it would appear if lying on a flat surface; and

Figure 4 is a view of a portion of the hobble, to a somewhat larger scale.

The hobble consists of two hooks 5 of such size and shape that they will fit about the tendon above the hocks. The hooks have been shown 10 as made from metal, such as steel, but may be made from round metal bars if desired. The outside ends 6 of the hooks are longer than the inner ends and have attached to them, preferably by means of rivets 7, leather flaps 8. The flaps are 15 shaped in the manner shown in Figs. 3 and 4 and may be described in a general way as spatulated. It will be seen from Figs. 3 and 4 that the flaps widen in a symmetrical manner outwardly from the place where they are fastened to the 20 hooks. In the actual hobble the flaps measure about 7 inches in length and about 3½ inches in width at their widest portions. The size can, of course, be varied within reasonable limits.

Attached to the outside of each flap at its 25 widest portions is a strap 9 that is secured at its ends to the flaps and is referred to herein and in the claims as loops.

Secured at one end to one of the flaps is a strap 10. The means employed for attaching the strap 30 10 to the flap comprises a metal D having a straight side 11 and a convex side 12. The straight side 11 is enclosed by a loop 13 that is secured to the flap by means of a rivet 14, or by any other or additional means. One end of 35 strap 10 encloses the curved side 12 and is permanently attached to the D ring by means of a rivet 15 and in addition by stitching if desired.

The strap 10 passes through the guide slot or loop formed by strap 9 and can be moved transversely of the flap between the extreme positions indicated by the dot and dash lines. The other end of strap 10 is provided with a number of openings 16 and passes through the loop on the other flap. Attached to the other flap, the one 45 to the left in Fig. 3, is a buckle 17 and a guide loop 18. The buckle and guide loop are secured to the flap by means of a leather bight 19. The buckle has the usual tongue 20 that cooperates with the holes 16.

50 The hobble is attached to the cow in the manner shown in Fig. 1 and can be adjusted in length by means of the strap 10 and the buckle.

An inspection of Figs. 1 and 2 shows that the strap 10 is separated from the cow's body by the 55

flaps 8 and as a result it may slide transversely of the flaps between the limiting positions, indicated by broken lines in Fig. 4, without danger of chafing and irritating the skin.

5 In case the cow should struggle to free herself from the hobble, she cannot get injured, as she nearly always is, where straps, ropes or chains are used and contact directly with the skin of the cow.

10 The feature of novelty in this case resides in the protective elements or flaps 8, and in the manner in which the strap 10 is secured to the flaps and guided in its transverse movements by the loop straps 10.

15 Having described the invention what is claimed as new is:

1. An article of manufacture comprising a metal hook, for use in a cow hobble and adapted to engage with the rear leg tendon directly above the hock, and a spatula shaped leather flap attached at its narrow end to one end of the hook and provided on its outside with a strap extending crossways thereof and secured thereto at its ends to form a guide loop.

25 2. A hobble of the type employed to prevent cows from kicking and which employs two interconnected hooks for engaging the tendons above the hocks, comprising an irritation preventing leather flap attached to one end of each hook and of sufficient length to extend along the outside of the cow's legs and inwardly across the front thereof, a strap interconnecting the flaps, and guide loops comprising straps extending transversely of and attached at their ends to the flaps, the guide loops thus formed being of considerable greater length than the width of the

straps, whereby the latter may slide transversely of the flaps.

3. A hobble of the type in which two hooks are engaged about the tendons of a cow's hind leg and connected by a tension member passing in front of the legs, comprising a leather flap attached to the outside end of each hook and of sufficient length to extend to the front of the leg and curve inwardly, the flaps being wider at their outer ends than at the ends attached to the hooks, a strap, means for attaching the strap to both flaps, at points spaced some distance from the free ends of the flaps, the attaching means permitting the strap to slide transversely of the flaps and to turn about the attaching means as a pivot, and each flap having a guide strap attached at its ends to the flap and passing over the first mentioned strap, whereby a guide loop is formed which is of greater length than the width of the first mentioned strap so that it may slide transversely of the flaps, the latter serving to protect the cow's legs from being irritated by the movement of the strap.

4. In a hobble of the type in which two hooks are engaged about the tendons of a cow's hind leg and connected by a tension member passing in front of the legs, said tension member comprising a leather flap attached to the outside end of each hook and of sufficient length to extend to the front of the leg and curve inwardly, a strap attached to both flaps at a point spaced some distance from the free ends of the flaps, and a second strap secured at its ends to each flap and passing over the first named strap, whereby a guide loop is formed.
